CHARLES M. HILSEE, OF PHILADELPHIA, PENNSYLVANIA, ASSIGNOR TO UNDERWOOD
TYPEWRITER COMPANY, OF NEW YORK, N. Y., A CORPORATION OF DELAWARE.

TYPEWRITING-MACHINE.

1,331,768.

Specification of Letters Patent. Patented Feb. 24, 1920.

Application filed November 26, 1917. Serial No. 203,890.

To all whom it may concern:

Be it known that I, CHARLES M. HILSEE, a citizen of the United States, residing in Philadelphia, in the county of Philadelphia and State of Pennsylvania, have invented 5 certain new and useful Improvements in Typewriting-Machines, of which the following is a specification.

This invention relates to means for collating 10 sheets upon the platens of typewriting machines, particularly the revoluble platens of front-strike machines, although certain of the principal features of the invention are available also for flat-platen typewriters.

Heretofore, in collating sheets, as for example, in collating an invoice (or statement) 15 upon a ledger sheet, it has been the practice to introduce the ledger sheet and advance it around the platen and register it, and then to hold it there during the operation of introducing the statement sheet and passing it around the platen over the ledger sheet and into the desired registration with said ledger sheet; and thereupon usually both 20 sheets are drawn backwardly as a unit by the rolls of the typewriter until the proper line upon the statement is in position to receive the impressions of the types.

It has been the preferred practice in collating sheets in this manner, to provide each 25 sheet with a row of registering perforations, usually along each side border of the sheet, and to arrange upon the typewriting machine pins or studs to be engaged by these 30 perforations, for accurately collating the sheets; the studs and perforations being depended upon to bring the sheets into the exact desired register with each other, so that the typed lines will fall in their proper places 35 upon each of the collated sheets.

It is found in practice difficult to locate the 40 perforations with the required accuracy in manufacturing the sheets. Moreover, the perforation is an expense, and it necessitates making the sheet of greater width than 45 would otherwise be required, thus adding to the cost. The statement or invoice sheet particularly has to be increased materially in width, so that its side perforations may 50 match those of the wide ledger sheet; and this is objectionable not only by reasons of the expense, but also because the widened statement sheet covers up certain special columns upon the ledger sheet in which it is 55 intended to type figures and items which it

is not desired to have appear upon the statement sheet.

The main objects of my invention are to reduce the cost of making the sheets, to expedite the introduction and collation thereof 60 in the machine, to permit the use of narrow statement or invoice or other temporary sheets, to avoid dependence upon side perforations for securing the desired accuracy of registration of one sheet relatively to 65 another, and to simplify the construction and operation of the machine.

Other features and advantages will hereinafter appear.

In the accompanying drawings,

Figure 1 is a perspective front view of the carriage of an Underwood front-strike typewriting machine, showing my improvements applied thereto in one form.

Fig. 2 is a sectional side elevation showing 75 ledger, statement and carbon sheets in position to begin typing thereon.

Fig. 3 is a front elevation showing the sheets collated and ready for the typing operation.

In carrying out the invention, instead of first introducing and registering the ledger or other inner sheet 10, the invoice, statement or other outer sheet 11 is introduced first. It is inserted at the back of the platen 85 and thrust forward under and up in front of the same. For this sheet a special collating table 12 is erected at the delivery side of the typewriter platen 9, upon which to adjust the statement sheet to position for 90 typing the first line thereon, this collating table having at its top a gage 13 for gaging the leading edge of the sheet, and also having, along preferably one side, a gage 14 for the side edge of said sheet. The sheet 95 may be squared or trued by either gage, preferably by the top gage 13, which has ample length for this purpose. Other gaging and squaring means may be employed for the leading portion of the sheet.

The statement or outer sheet 11 having thus been introduced and squared to printing position, with the body of the statement extending between the platen and the released bottom feed rolls 15, is now held 105 temporarily in position without the aid of said bottom feed rolls 15, which must remain cast off during the introduction of both the statement sheet 11 and the ledger sheet 10. This temporary holding means com- 110

prises a pair of yielding fingers or clips 16, which are arranged upon said collating table to catch upon the face of the statement sheet, holding it against the front surface 5 of the collating board 12, a light pressure being sufficient to retain the sheet; said clips having turned-up front ends for convenience in inserting the sheet thereunder; the clips yielding to the edgewise thrust of the sheet.

10 The ledger or record sheet 10 is then introduced at the back of the platen, and passed down between the platen and the statement sheet 11; the carbon sheet 17 having been inserted at the same operation as 15 the statement sheet. The ledger sheet 10 is thrust forwardly and upwardly around the platen, between the same and the carbon and statement sheets, and passes up behind the collating table 12, a passage for the sheet 20 being left at 17^a between the table 12 and platen 9.

The ledger sheet 10 is preferably squared by the aid of the sides 18 of a chute 19, which preferably is erected at the rear or 25 introductory side of the platen, and continues at 18^a around the under side thereof and merges at the delivery side of the platen into a separate collating table or board 20, which stands in rear of the collating table 30 12, already referred to, upon which the statement is being temporarily held. The sides 21 of the board 20 form in effect continuations of the sides 18 of the chute, and the ledger sheet fits between said sides, so as 35 to be squared and guided accurately thereby. The chute may be omitted in some cases if desired. The chute may be supported by means of studs 22 projecting inwardly from the frame 23 that carries the platen 9, or by 40 other suitable supports, and the plates forming the rear sides or gages 18 may merge at their lower portions (Fig. 2) with the plates or gages 21; said plates also serving to support the table 20. Arms or bridges 24 may 45 extend inwardly from the upper edges of the gages or plates 21, to form mounts to support the front collating table 12; or the parts 24 may meet to form a bar to which 12 may be fastened, 12 being thus spaced from 20, to afford a passageway for the 50 sheets 10.

In passing up in front of the platen 9, the ledger sheet 10 comes under the control of a pair of special rolls 25, which run upon 55 preferably the delivery side of the platen. The ledger sheet is made of greater width than the statement sheet 11, partly for the purpose of affording room to type figures thereon which it is not desired to have appear upon the statement sheet, and partly for the purpose of enabling said rolls 25 to engage and feed the ledger sheet. These rolls 25 may be raised to open a path for the upward passage of the leading edge of 60 the ledger sheet; being for this purpose

mounted upon arms 25^a, fixed at their upper ends upon a rock-shaft 25^b mounted in standards 25^c erected upon the opposite studs 22. Double-acting springs 25^d, engaging said arms 25^a, may hold the rolls either 70 against the platen 9 or in an elevated position. These rolls are sufficiently separated to escape the statement sheet 11, Fig. 1, so that the ledger sheet may be advanced or retracted by means of rolls 25 and platen 9, 75 while the statement sheet 11 (with carbon 17) remains stationary, so that the desired relative positioning of the two sheets may be secured by adjusting the under sheet 10.

After the ledger sheet 10 has reached a 80 position between its rolls 25 and the platen, the usual platen knob 26 may be grasped to rotate the platen, and thereby feed up the ledger sheet by the aid of said rolls; the feed rolls 15 which run upon the bottom of the 85 platen still remaining released.

The operator thus brings the ledger sheet to such position that the next line to be written thereon will coincide with the printing point of the typewriting machine, or, in 90 other words, will lie exactly beneath or in register with the line upon the statement sheet which is to be typed. As an aid, the operator may position the ledger sheet by reference to the front wing scales 27 usually 95 provided upon said Underwood machine to indicate the writing line. The operator can readily see portions of the lines 28 previously typed upon the ledger sheet, and hence can readily adjust said sheet so that the 100 next line of typing will fall in its proper place. This brings the ledger sheet into proper register with the statement 11, whose position with reference to the printing point has been mechanically determined by the 105 gage 13.

The operator then restores the bottom feed rolls 15, so as to hold the sheets smoothly against the platen. Said rolls may also effect the line-feeding of the statement and ledger sheet jointly if required; and in such case, the operator may withdraw the statement sheet from beneath the clips 16; so that the sheet may advance over the clips and independently thereof during line-feeding operations. 115

If the same statement and ledger sheet are desired to be re-introduced into the machine upon a subsequent day, to have another item entered thereon, the operator may introduce 120 the sheets as before, and may then, by means of the platen knob, advance them as a unit a distance equal to one or two lines, to bring them to proper position to receive the new item, which it is desired to type at a point 125 just below the item last entered, as aforesaid. In this way, the statement may be filled up from day to day until the end of the month; the corresponding entries being, of course, made upon the ledger sheet. In 130

the next month the same ledger sheet may be used with a fresh statement; the ledger sheet being, however, advanced far enough by the platen knob 26 to bring the succeeding month's entries below those last made upon the ledger sheet. The bottom feed rolls 15 are useful both when more than a single line is to be typed upon the statement, and also when it is desired to adjust the 10 sheets up or down after introduction, and before typing the first line.

It will be seen that the invoice sheet is readily introduced and brought to its printing position with unfailing accuracy, and that it is only necessary to insert the leading edge of the invoice sheet under the clips, which can be done by merely thrusting the 15 sheet up under them, as they have very light tension and yield readily to the insertion of 20 the sheet between the same and the table.

It will further be seen that it is unnecessary to collate one sheet over another one which has previously been placed in the machine, and which it would not be convenient 25 to retain in position without the use of registering pins, or the like, ranged along the side borders of the sheet. It will be understood that the ledger sheet slips readily around the platen between the same and 30 the previously-inserted statement or invoice sheet, which is held upon its collating table, or between the platen and the carbon sheet which was introduced into the machine at the same time as the invoice sheet; the 35 lower feed rolls being cast off during the introduction of both sheets, so that there is left open a passage for the ledger sheet between the platen and the other sheets. If desired, the statement, carbon and ledger sheet may 40 be dropped into the machine at the same time, with the statement in advance of the ledger sheet, and the sheets thrust forward and up in front of the platen, the statement being conducted up in front of table 12 45 and adjusted and clipped while the ledger sheet remains unadjusted, and said ledger sheet being then thrust forwardly under the rolls 25 and set to position in the manner already explained.

50 It will also be seen that the statement sheet, when thus mechanically brought to exact printing position, may serve as a guide for locating the ledger sheet in rear thereof, since enough of the ledger sheet can be seen 55 at the sides of the invoice sheet to enable one sheet to be brought into the desired longitudinal register with the other; or the usual wing scale in front of the platen may be relied upon, as explained, for positioning 60 the ledger sheet accurately up or down. When the sheets have once been introduced and brought into the desired registration with each other, the typing may proceed without further manipulation of either 65 sheet, and it is not necessary to withdraw

the invoice sheet from the clips unless the typing is to make more than one line upon the sheet. It is rendered unnecessary to keep track of the engagement of pins with perforations along the sides of the sheets, 70 and to see that the paper is properly withdrawn from the pins at numerous points at each side of the sheet, as heretofore. The statement sheet needs to be of no greater than normal width, and the ledger sheet 75 may be made of as great width as may be desired, without being confronted with the necessity of increasing the width of the statement sheet to the same extent. Expense is saved in manufacturing the statement sheet because of this saving in width; and it is no longer necessary to perforate 80 additional side lines down the statement sheet to enable the waste margins to be torn off; and the statement sheets as sent out to 85 the customer have clean-cut edges instead of rough edges. The operator is enabled to see a large part of the ledger sheet, which is an advantage to be appreciated, since heretofore all or the principal portion of 90 the typing field in the ledger sheet has been covered up by the widened statement sheet. Moreover, the accuracy of collation of the sheets does not depend upon perforations in their side margins, which are apt to be in- 95 accurately made, but they depend merely upon the operator advancing the ledger sheet singly to a position to bring the writing line thereon into register with the usual scale, which is an operation readily performed with accuracy. Other advantages 100 will be clear from the drawings and specification.

Variations may be resorted to within the scope of the invention, and portions of the 105 improvements may be used without others.

Having thus described my invention, I claim:

1. The combination with a revoluble platen, of a collating-board mounted at the 110 delivery side thereof, upon which to collate an outer sheet, said collating-board having a leading-edge and side-gaging means, and a second collating-board behind the first.

2. The combination with a revoluble 115 platen, of a collating-board mounted at the delivery side thereof, upon which to collate an outer sheet, said collating-board having a leading-edge gage and a side-guide, and a second collating-board behind the first 120 and of greater width, said second collating-board having side-guides.

3. The combination with a revoluble platen, of a collating-board mounted at the 125 delivery side thereof, upon which to collate an outer sheet, said collating-board having a leading-edge gage and a side-guide, and a second collating-board behind the first and of greater width, said second collating-board having side-guides, and a sheet-pas- 130

sage being left between the first collating-board and the platen.

4. The combination with a revoluble platen, of a collating-board mounted at the 5 delivery side thereof, upon which to collate an outer sheet, said collating-board having a leading-edge gage and side-gaging means, a second collating-board behind the first and of greater width, said second collating- 10 board having side-gages or guides, and a sheet-passage being left between the first collating-board and the platen, and rolls to press the under sheet upon the platen only laterally outside of the outer sheet, so 15 as to coöperate with the platen to feed the under sheet while the outer sheet is stationary.

5. The combination with a revoluble platen, of a collating-board mounted at the 20 delivery side thereof, upon which to collate an outer sheet, a second collating-board behind the first, said second collating-board having side-guides, feeding means to bear upon the under sheet only laterally outside 25 of the outer sheet, so as to coöperate with the platen to feed the under sheet after the outer sheet has been collated, and means to retain the outer sheet upon the first collating-board during the insertion and adjustment of the inner sheet.

6. The combination with a revoluble platen, of a collating-board mounted at the delivery side thereof, upon which to collate an outer sheet, a second collating-board behind the first and of greater width, said second collating-board having side-gages, feeding means to bear the under sheet against the platen only laterally outside of the outer sheet, so as to coöperate with the 35 platen to feed the under sheet independently of the outer sheet, means to retain the outer sheet upon the first collating-board during the insertion and adjustment of the inner sheet, and releasable feed rolls to run upon the bottom of the platen.

7. The combination with a revoluble platen, of a collating-board mounted at the delivery side thereof, upon which to collate an outer sheet, said collating-board having 50 a leading-edge gage, a second collating-board behind the first and of greater width, said second collating-board having side-guides, and a chute at the introductory side of the platen, comprising sides which extend around the platen to merge into the sides of the second collating-board.

8. The combination with a revoluble platen, of a collating-board mounted at the delivery side thereof, upon which to collate 60 an outer sheet, said collating-board having a leading-edge gage, a second collating-board behind the first and of greater width, said second collating-board having side-guides, and a sheet-passage being left between the first collating-board and the platen, rolls

to bear the under sheet against the platen only laterally outside of the outer sheet, so as to coöperate with the platen to feed the under sheet after the outer sheet has been collated, means to retain the outer sheet 70 upon the first collating-board during the insertion and adjustment of the inner sheet, a chute at the introductory side of the platen, comprising sides which extend around the platen and merge into the sides of the second 75 collating-board, and releasable feed rolls to run upon the bottom of the platen.

9. In a typewriter, the combination with a platen, of means for holding a work-sheet 80 in predetermined relation therewith for typing, said holding means comprising a paper-table at the delivery side of said platen, an end gage for said sheet, and a clip, the relation between said table, gage 85 and clip being such that the clip will be rendered effective by the advancement of the leading edge of said sheet along said table into gaging relation with said gage.

10. The combination with a revoluble 90 platen and a platen frame, of a collating-board at the delivery side of the platen for an outer sheet, and a second collating-board in rear of the first for an inner sheet, a passage being left for the inner sheet between the first collating-board and the platen.

11. The combination with a revoluble platen and a platen frame, of a collating-board at the delivery side of the platen for 100 an outer sheet, a second collating-board in rear of the first for an inner sheet, and means for supporting said collating-boards upon said platen frame, said supporting means including a mount arranged above the 105 platen and extending out from the side of the first collating-board, a passage for the inner sheet being left between the platen and said outer collating-board and mount.

12. The combination with a revoluble 110 platen and a platen frame, of a collating-board at the delivery side of the platen for an outer sheet, and a second collating-board in rear of the first for an inner sheet, the second collating-board being of substantially 115 greater width than the first.

13. The combination with a revoluble platen and a platen frame, of a collating-board at the delivery side of the platen for an outer sheet, and a second collating-board 120 in rear of the first for an inner sheet, the second collating-board being of substantially greater width than the first, and having opposite sides or gages for controlling the inner sheet.

14. The combination with a revoluble platen and a platen frame, of a collating-board at the delivery side of the platen for an outer sheet, a second collating-board in rear of the first for an inner sheet, and 130

means to clip the outer sheet to the first collating-board.

15. The combination with a revoluble platen and a platen frame, of a collating-board at the delivery side of the platen for an outer sheet, a second collating-board in rear of the first for an inner sheet, and rolls to run upon the platen only laterally outside of the outer sheet, to feed the inner sheet while the outer sheet remains held by the clipping means.

16. The combination with a revoluble platen and a platen frame, of a collating-board at the delivery side of the platen for an outer sheet, means to hold the work thereon, a substantively wider collating-board in rear of the first and having side-guides for an inner sheet, and means for supporting said collating-boards upon said platen frame, said supporting means including mounts or devices extending above the platen from the sides of the first-collating board, a passage for the inner sheet being left between the platen and said first collating-board and mounts.

17. The combination with a revoluble platen and a platen frame, of a collating-board at the delivery side of the platen for an outer sheet, means to hold the work thereon, a substantively wider collating-board in rear of the first and having side-guides for an inner sheet, means for supporting said collating-boards upon said platen frame, said supporting means including mounts or devices extending above the platen from the sides of the first collating-board, a passage for the inner sheet being left between the platen and said first collating-board and mounts, and rolls to run upon the platen only at the sides of the outer sheet, to feed the inner sheet while the outer sheet remains held by the holding means.

18. The combination with a revoluble platen and a platen frame, of a collating-board at the delivery side of the platen for an outer sheet, means for supporting said collating-board upon said platen frame, said supporting means including a mount extending above the platen from the side of said collating-board, a passage for an inner sheet being left between the platen and said collating-board and mount, opposite sides or gages at the delivery side of the platen and in rear of said collating-board, for controlling the inner sheet, and means to support said side-gages.

19. The combination with a revoluble platen and a platen frame, of a collating-board at the delivery side of the platen for an outer sheet, means for supporting said collating-board upon said platen frame, said supporting means including a mount extending above the platen from the side of said collating board, a passage for an inner sheet being left between the platen and said

collating board and mount, opposite gages for the side edges of the inner sheet at the delivery side of the platen and in rear of said collating-board, for controlling the inner sheet, means to support said side-gages, and means to hold the outer sheet to said collating-board.

20. The combination with a revoluble platen and a platen frame, of a collating-board at the delivery side of the platen for an outer sheet, means for supporting said collating-board upon said platen frame, said supporting means including a mount extending above the platen from the side of said collating-board, a passage for an inner sheet being left between the platen and said collating-board and mount, opposite gages for the side edges of the inner sheet at the delivery side of the platen and in rear of said collating-board, for controlling the inner sheet, means to support said side-gages, means to hold the outer sheet to said collating-board, and rolls to run upon the platen only laterally outside of the outer sheet, to feed the inner sheet while the outer sheet remains held upon said collating-board.

21. The combination with a revoluble platen and a platen frame, of a collating-board at the delivery side of the platen for an outer sheet, a second collating-board in rear of the first for an inner sheet, and means for supporting said collating-boards upon said platen frame, said supporting means including mounts projecting oppositely from the sides of the first collating-board, a passage for the inner sheet being left between the platen and said first collating-board and mounts.

22. The combination with a platen and opposite side-gages at the introductory side of the platen for an inner sheet, of side-gages at the delivery side of the platen for said inner sheet, and a collating-table at the delivery side of the platen to occupy a position between said inner sheet and an outer sheet that is collated upon said table.

23. The combination with a platen and opposite side-gages at the introductory side of the platen for an inner sheet, of side-gages at the delivery side of the platen for said inner sheet, and a collating-table at the delivery side of the platen to occupy a position between said inner sheet and an outer sheet that is collated upon said table, said collating-table having means to square and register the sheet relatively to the printing line.

24. The combination with a platen and opposite side-gages at the delivery side of the platen for an inner sheet, of a collating-table at the delivery side of the platen to occupy a position between said inner sheet and an outer sheet to be collated thereon.

25. The combination with a platen and

opposite side-gages at the delivery side of the platen for an inner sheet, of a collating-table at the delivery side of the platen to occupy a position between said inner sheet 5 and an outer sheet to be collated thereon, and means upon said table to retain said outer sheet.

26. The combination with a platen and opposite side-gages at the delivery side of the platen for an inner sheet, of a collating-table at the delivery side of the platen to occupy a position between said inner sheet 10 and an outer sheet to be collated thereon, means upon said table to retain said outer sheet, and means to feed the inner sheet 15 while the outer sheet is so retained.

27. The combination with a platen and opposite side-gages at the introductory side of the platen for an inner sheet, of side-gages at the delivery side of the platen for 20 said sheet, and a collating-table at the delivery side of the platen to occupy a position between said inner sheet and an outer sheet collated upon said table; said side-gages being all sufficiently separated to 25 guide an inner sheet of substantially greater width than said table.

28. The combination with a platen and opposite side-gages at the introductory side 30 of the platen for an inner sheet, of side-gages at the delivery side of the platen for said sheet, a collating-table at the delivery side of the platen to occupy a position between said inner sheet and an outer sheet 35 collated upon said table; said side-gages being all sufficiently separated to guide an inner sheet of substantially greater width than said table, and feeding means to engage the borders of said inner sheet to feed the same 40 independently of the outer sheet.

29. The combination with a revoluble platen, of a collating-board at the delivery side thereof for an inner sheet, a collating-board also mounted at the delivery side of 45 the platen to occupy a position between said inner sheet and an outer sheet collated thereon, and a leading-edge gage upon the last-mentioned collating-board to register a sheet in its final position for typing a line thereon.

50 30. The combination with a revoluble platen, of a collating-board at the delivery side thereof for an inner sheet, a collating-board also mounted at the delivery side of the platen to occupy a position between said 55 inner sheet and an outer sheet collated

thereon, a leading-edge gage upon the last-mentioned collating-board to register a sheet in its final position for typing a line thereon, and releasable feed rolls to run upon the bottom of the platen in such position that 60 said sheets are collated while extending between said rolls and the platen.

31. The combination with a revoluble platen, of a collating-board at the delivery side thereof for an inner sheet, a collating-board also mounted at the delivery side of the platen to occupy a position between said inner sheet and an outer sheet collated thereon, a leading-edge gage upon the last-mentioned collating-board to register a sheet in 70 its final position for typing a line thereon, and releasable feed rolls to run upon only the side margins of the inner sheet, to feed the same while the outer sheet remains stationary. 75

32. The combination with a revoluble platen, of a collating-board at the delivery side thereof for an inner sheet, a collating-board also mounted at the delivery side of the platen to occupy a position between said inner sheet and an outer sheet collated thereon, a leading-edge gage upon the last-mentioned collating-board to register a sheet in 80 its final position for typing a line thereon, releasable feed rolls to run upon the bottom of the platen, and in such position that said sheets are collated while extending between said rolls and the platen, and releasable feed rolls to run upon only the side 85 margins of the inner sheet to feed the same 90 while the outer sheet remains stationary.

33. The combination with a revoluble platen, of a collating board at the delivery side thereof for an inner sheet, a collating-board also mounted at the delivery side of 95 the platen to occupy a position between said inner sheet and an outer sheet collated thereon, a leading-edge gage upon the last-mentioned collating-board to register a sheet in its final position for typing a line thereon, 100 means to hold the work upon the last-mentioned collating-board, and feed rolls to run upon only the side margins of the inner sheet to feed the same while the outer sheet remains stationary.
